UNITED STATES PATENT OFFICE.

EDWARD M. CUMMINGS, OF CATONSVILLE, MARYLAND.

DESIGN FOR A LAMP.

No. 38,660.

Specification for Design.

Patented July 9, 1907.

Application filed June 5, 1907. Serial No. 377,469. Term of patent 14 years.

To all whom it may concern:

Be it known that I, EDWARD M. CUMMINGS, a citizen of the United States, residing at Catonsville, in the county of Baltimore, State of Maryland, have invented a new, original, and ornamental Design for Lamps, of which the following is a specification.

Reference is had to the accompanying drawing, forming a part hereof.

The figure is a perspective view of a lamp, showing my new design.

I claim:

The ornamental design for a lamp, as shown.

EDWARD M. CUMMINGS.
